HOT WATER CIRCULATOR

Morris Parnes and Abraham Gruber, New York,
N. Y., assignors to Elliott M. Feinberg, New
York, N. Y.

Application February 4, 1948, Serial No. 6,204

10 Claims. (Cl. 126—383)

1

The present invention relates to a portable hot water circulating device.

It is an object of the present invention to provide a device of the character described which will convert a mass of boiling water in a receptacle into a circulating, constant-flow stream of hot water.

It is also an object of the present invention to provide a device of the character described which will permit the utilization of the constant-flow stream of hot water for practical application.

It is another object of the present invention to provide a device of the character described which may be utilized with practically any type and substantially any size of open ended container or receptacle capable of holding water and withstanding the heat necessary to bring water to a boil, whereby the production of a constant flow stream of hot water is made possible whenever a pot and heater are available.

It is still another object of the present invention to provide a device of the character described which is economical in the use of water and heat by repeatedly utilizing the same mass of water with a minimum of loss and waste and with the consequent need for only infrequent replenishment by the addition of cold water.

It is a further object of the present invention to provide a device of the character described which is quiet and substantially noiseless in operation and which is otherwise handy, desirable and convenient to use.

It is a still further object of the present invention to provide a device of the character described which is compact; which is economical to produce and which is simple, easy and economical to operate.

The device of the present invention is of particular advantage for use in the art of mechanical dentistry and in other arts wherein wax molds are utilized, or wax mold linings, for producing castings of plastic materials or gold or other precious metals. The most convenient method for accomplishing the melting away of the wax from the casting or from the plaster mold has been found to be the application and use of hot water; a method very extensively used in the art.

Hot water for the above purpose has been generally obtained from a pot or like container set over a stove or similar heating device. The mold and castings were held over the pot and the hot water applied with a ladle or the like.

The foregoing method for applying hot water

2

to the wax mold, besides being clumsy, laborious and time-consuming, had the additional disadvantage of being difficult to effect complete and clean melting away of the wax from the mold or casting, without frequent changes of the water, which involved additional waste of time and fuel until it was heated to the proper temperature. The reason for such need is the fact that, after limited use, the water became coated with molten wax which floated on its surface and such molten wax was picked up by the ladle with the water and would readhere on the mold or casting when the water was poured thereon.

The present invention provides a device which will eliminate all of the foregoing disadvantages by converting the same water in the same pot as heretofore used into a constantly flowing, circulating, clean stream of hot water, always utilizing the clean, bottom water of the pot for circulation and disposing the stream of water in a position to permit the holding of the work thereunder, for clean, rapid, complete and convenient dissolving of the wax.

The foregoing and other advantages and superiorities of the device of the present invention will become more readily apparent to those skilled in the art from the preferred embodiment thereof shown in the accompanying drawings and from the description thereof following. It is to be understood, however, that such embodiment is shown by way of illustration only, to make the principles and practice of the invention more readily comprehensible, and without any intent of limiting the invention to the specific details therein shown.

In the drawings:

Fig. 1 is a perspective view of one preferred embodiment of the device of the present invention; and

Fig. 2 is a vertical sectional view through the same and through a hot water container in which it is disposed over a heater.

Referring more specifically to the accompanying drawings, a pot or similar open ended container 10, suitable for having the water 11 heated therein, as by a heating device over which it is arranged, such as the burner 12, is more or less diagrammatically illustrated. The pot 10 may, preferably, be straight walled or may have its wall slightly outwardly tapering, as illustrated, to provide ample surface area for working thereover.

Set up within the pot 10, is the hot water circulating device of the present invention, generally designated as 13. The device 13 comprises an

inverted, opened bottom, hollow base portion 14, which may be of conical, dome or similar shape and of a size adapted to cover a substantially large area of the bottom of the pot 10. The base 14 is provided at or adjacent its bottom edge with a plurality of apertures 15, for the circulation of the water 11 therethrough.

The base 14 is also provided at approximately its highest point with an opening 16, into which is set a riser tube 17, of a height to extend a substantial distance above the edges of the pot 10.

The upper end of the riser supports a water chamber or reservoir 18, consisting of a lower, preferably oval shaped receptacle portion 19, and a correspondingly shaped cover portion 20, which fits tightly and securely within or over the receptacle 19. The cover 20 may, if desired, be further securely attached in place as by means of screws passing through the cover 20 and engaging in the edges of the receptacle portion 19, in a manner readily understood and not thought necessary to be specifically illustrated.

One end of the receptacle portion 19, may be of reduced depth and have a level floor portion 21, in which may be formed the opening 22 adapted to fit over the riser 17. The opening 22, may be formed with an inwardly extending sleeve 23, which may be provided with the internally formed threads 24, by which it may be supported and engaged on the corresponding threads formed on the end of the riser 17, forming a steady, secure and substantially liquid proof connection therewith. It will be apparent that other suitable means for supporting and securing the chamber 19 on the riser 17, may be utilized.

The opposed end of the receptacle portion 19 may be formed with a depending nozzle 25, having the outlet opening 26 formed therein. Such opening 26 is formed to be of lesser size, as one-half or one-third of the size of the inlet opening formed by the end of the riser 17, entering the chamber 18.

Set into the floor portion 21, in suitable openings provided therein for the purpose, are a steam escape tube 27, extending preferably above the end of the riser 17 and a water overflow tube 28, extending preferably to a point below the end of the riser 17.

In operation, the boiling water in the pot 10, which is encompassed within the base 14, rises by the steam pressure generated through the opening 16 into the riser 17, and thence into the water chamber 18. In the chamber 18, the mixture of water and steam separates; the water falling to the bottom and the steam escaping through the tube 27. As the outlet opening from the water chamber 26 is of lesser size than the inlet through the riser, the water 11 accumulates on the bottom of the chamber 19, and is discharged therefrom, through the opening 26 in a constant flowing stream; thus converting the intermittent, pulsating sprays of water coming in through the riser 17, into a constantly flowing stream capable of performing continuous, wax melting work. Any excess water that may come into the chamber 19, will be discharged through the tube 28, thereby establishing a fixed water level within the chamber 19.

In order to conserve the hot water as well as to render the operation of the device silent, by dampening out the noise made by the spouting steam and water mixture, the chamber may have a depending, downwardly tapering sleeve 30 formed preferably integrally therewith, the up-

per end of such sleeve encompassing the opening 22, and the openings for the tubes, 27 and 28, and the lower end thereof tapering to fit snugly around the riser 17. The sleeve 30 may have a plurality of apertures, such as 31, formed therein adjacent its lower end.

By this construction, the sleeve 30, not only serves to steady the chamber 18, on the riser 17, but also to condense any steam escaping through the tube 27, and to return such condensed steam as well as the overflow water from the tube 28, back into the pot 10, and serves as well to deaden and silence the noise otherwise incident to the operation of the device.

In order to provide maximum working area over the pot 10, the base 14, and riser 17, may be so formed and arranged that the riser 17, emerges from the pot 10, up against or close to the wall thereof, so that the nozzle 25 is disposed adjacent the center of the pot opening. For that purpose the riser 17 may be sloped or bent along its lower portion, or preferably, as illustrated, the base 14 may be so shaped that it has its apex at one end thereof wherein the opening 16 is formed, so that by merely disposing the device along a side of the pot, the riser will emerge therefrom in suitable position. Additional advantage may be attained, particularly for use with pots having sloping sides, by setting the riser into the base at slight slant, as illustrated.

This completes the description of one embodiment of the device of the present invention. It will be readily apparent that many modifications and variations thereof may be made by any one skilled in the art, in accordance with the principles of the invention hereinabove set forth and without the use of any inventive ingenuity. We desire, therefore, to be protected for any and all such variations and modifications that may be made within the spirit of the present invention and scope of the claims hereto appended.

What we claim is:

1. A device for circulating a constant flow stream of hot water in an open top water containing vessel comprising an eccentrically upwardly tapering hollow base having a wide open bottom by which it is adapted to rest on the bottom of a vessel and an opening formed at approximately the apex thereof, an open ended riser tube set into the said opening, a hollow body providing a chamber supported at the free end of said riser and communicating with the opening of the riser at said end, said chamber having a single outlet opening at its bottom of a lesser size than said riser opening communicating therewith, whereby an intermittent, spouting stream of hot water entering the said chamber through said riser is accumulated therein to provide a constant flow stream out of said outlet opening.

2. The device of claim 1, wherein said chamber is substantially closed and is provided with outlet means for excess accumulated water to thereby maintain a substantially constant water level therein.

3. The device of claim 1, wherein the said chamber is substantially closed, said hollow body comprising a bottom portion and a tightly fitting cover portion and wherein said bottom portion is provided with outlet means for excess accumulated water and for steam.

4. A device for circulating a constant flow stream of hot water in an open top water containing vessel comprising an eccentrically upwardly tapering base having its apex adjacent

an edge thereof, said base having a wide open bottom by which it is adapted to rest on the bottom of a vessel and having an opening formed at approximately the apex thereof, an open ended riser tube set into the said opening, a substantially closed receptacle supported at the free end of said riser tube and communicating with its opening at said end, said receptacle having a single outlet opening in its bottom of a lesser size than said riser opening communicating therewith, whereby an intermittent, spurting stream of hot water entering the said chamber through the said riser is accumulated therein to provide a constant flow stream of hot water through the said outlet opening.

5. The device of claim 4, wherein the said receptacle is of elongated shape and is supported at one end along its longer axis and is provided with its outlet opening at its other end.

6. The device of claim 4, wherein the said receptacle is formed with an arcuate top to thereby distribute the stream of water entering thereinto.

7. The device of claim 4, wherein the said receptacle is provided with apertures in the bottom thereof and with tubes set into the said apertures and extending into the said chamber, said tubes being of different heights with the lowermost adapted to serve as an overflow for excess accumulated water and the higher adapted to serve as a steam outlet.

8. The device of claim 4, wherein the said receptacle is of ovoid shape and said riser receiving opening is formed at one end thereof and said outlet opening is formed at the other end thereof.

9. The device of claim 4, wherein the said receptacle has apertures formed in the bottom thereof and open ended tubes are set into said

apertures extending into the interior of the chamber and are adapted to serve as outlet means for excess accumulated water and for steam.

- 5 10. The device of claim 4, wherein the said receptacle has a depending tube secured to the bottom thereof surrounding said riser receiving opening and adapted to fit over and engage the said riser, said tube having openings formed 10 therein and wherein the said receptacle has apertures formed in the portion of its bottom encompassed by the said depending tube and tubes set into the said apertures and extending into the interior of the receptacle and adapted to serve 15 as outlets for excess accumulated water and for steam.
